UNITED STATES PATENT OFFICE.

FERDINAND A. FRITZE, JR., OF CHICAGO, ILLINOIS, ASSIGNOR TO DURABLE BOX CO., OF CHICAGO, ILLINOIS, A CORPORATION OF ILLINOIS.

BOTTOM FOR KNOCKDOWN BOXES.

1,258,330.

Specification of Letters Patent.

Patented Mar. 5, 1918.

Application filed February 17, 1916. Serial No. 78,940.

To all whom it may concern:

Be it known that I, FERDINAND A. FRITZE, Jr., a citizen of the United States, residing at Chicago, in the county of Cook and State 5 of Illinois, have invented certain new and useful Improvements in Bottoms for Knockdown Boxes, of which the following is a description.

My invention belongs to that general class 10 of devices known as knock-down boxes, in which the various parts going to make up a box are detachably connected, so the box may be shipped in the knocked-down from the manufacturing point, or after use may 15 be knocked down and returned to the user to be used again and again. The particular invention in this case relates to the peculiar manufacture of the bottom of said boxes with the means for securing the same in 20 place. It has for its object the production of a bottom suitable for such purposes, which may be economically produced, and which may be readily assembled with the rest of the box or detached therefrom as the 25 other parts are disconnected, and at the same time serves to firmly and rigidly hold the bottom in place when in use.

To this end my invention consists in the 30 novel construction, arrangement and combination of parts herein shown and described, and more particularly pointed out in the claim.

In the drawings, wherein like reference 35 characters indicate like or corresponding parts,

Figure 1 is a longitudinal section through the box from back to front, illustrating my invention;

Fig. 2 is a partial section substantially in 40 line 2—2 of Fig. 1;

Fig. 3 is a similar section substantially in 45 line 3—3 of Fig. 2, and

Fig. 4 is a fragmentary section partly broken away, illustrating an auxiliary part 50 of my invention.

In the drawings, 1 indicates the front wall of a box and 2 the rear wall thereof; 55 3 and 4 indicate the side walls of the box; 5 indicates the bottom and 6 the top.

The side and end walls are so constructed 60 that they may be readily connected in any preferred manner at their meeting corners to constitute a box form. The bottom is 65 preferably constructed of a size to snugly 70 fit within the form thus provided, and with

the top serving to strengthen the box and retain the form in its original shape or contour.

Arranged transversely the bottom are provided one or more cleats 7, as shown arranged toward the middle of the bottom. The cleat 7 is preferably longitudinally grooved as at 8, with a rod 9 seated in said groove and maintained therein between the cleat and the bottom 5, as indicated. At the 60 margin of the bottom the ends of the rod, as at 10, are bent upward and preferably seated in recesses or grooves formed in the walls of the box for their reception, with the extreme ends 11 bent outward and seated 65 in apertures or holes bored in the walls of the box for that purpose. This is clearly illustrated in Figs. 2 and 3. The bottom is also preferably provided with additional 70 cleats 12 near the margins thereof, and obviously, a similar construction may be employed here if desired. In the preferred 75 construction, however, the walls 1 and 2, as clearly shown in Figs. 1 and 4, have cleats 13 attached near the bottom of said walls, 80 thus becoming a component part thereof. The cleats 12 on the bottom of the box are 85 so positioned as to permit the extension 14 on the bottom to extend over and rest upon the cleats 13, while the cleats 12, as indicated, are seated in close contact with the cleats 13 when the box is set up. A hole 90 transversely bored into the cleat 12, registers with a similar hole formed in and preferably extending through the cleat 13, and 95 into the walls. As the box is set up, pins 15 are positioned in the several cleats 12—13, and the walls 1 and 2, as shown, serving to firmly engage the bottom of the box, preferably at right angles to the rod 9, at convenient points, and at a sufficient number of points to secure necessary rigidity and strength to the whole structure.

Obviously, the bottom carries with it the 100 rod 9, while the pins 15 are the only separable parts in the bottom structure to be provided for in assembling the box.

Practical demonstration shows that a box 105 constructed in this manner possesses great strength and durability. The whole box may be readily manufactured at the source of lumber supply at a minimum of cost, and may be shipped in the knocked-down or stored at the minimum cost. The boxes may be readily set up at the point where they 110

are to be used, by unskilled labor without driving or drawing a nail, or without special apparatus or machinery, and as stated, when so set up, possess great strength and durability. After use they may be readily disconnected and packed in the knocked-down form, as before stated, and returned to the user at a minimum of freight cost, where they may be readily assembled and used again and again.

In the drawings the box is shown as adapted for use by bottlers, in which a separate crate composed of slats 16, and transverse slats 17, are arranged in the box to separate the bottles.

Having thus described my invention, it is obvious that various immaterial modifications may be made in the same without departing from the spirit of my invention; hence I do not wish to be understood as limiting myself to the exact form, construction, arrangement and combination of parts herein shown and described, and more particularly pointed out in the claim.

What I claim as new and desire to secure by Letters Patent is:—

In a knock-down box, wall members,

adapted to be connected together to constitute a box form, a pair of the parallel wall members being provided with cleats 13 on the bottom thereof, with apertures formed therein, in combination with a bottom for said box, adapted to snugly fit within the box when set up, transverse cleats near the margin of said bottom, providing extensions 14 adapted to extend over and rest upon the cleats 13 on the sides, apertures formed in the cleats adapted to receive pins 15, firmly locking the cleats to the sides to prevent lateral motion, an additional cleat on the bottom longitudinally recessed, a rod 9 arranged in said recess and maintained between the cleat and the bottom, said rod bent upward at its ends and recessed into the proximate wall members with the ends of the rod bent outward engaging apertures formed in said wall members.

In testimony whereof, I have hereunto signed my name in the presence of two subscribing witnesses.

FERDINAND A. FRITZE, JR.
